UNITED STATES PATENT OFFICE.

GEORGE T. WELLS, OF WICHITA, KANSAS.

JETTY DEVICE.

No. 891,890.

Specification of Letters Patent. Patented June 30, 1908.

Application filed February 4, 1908. Serial No. 414,255.

To all whom it may concern:

Be it known that I, GEORGE T. WELLS, citizen of the United States, residing at Wichita, in the county of Sedgwick and State of Kansas, have invented certain new and useful Improvements in Jetty Devices, of which the following is a specification.

The present invention has for its object to provide a device of novel and peculiar formation for use in preventing the washing away of the banks of rivers or streams and also to recover land that has been encroached upon by the river or stream overflowing or washing away its banks.

In accordance with this invention, the device is projected into the stream or river at the point to be protected or to be reclaimed, said device consisting of a shaft and provided with one or more wings arranged lengthwise thereof.

The invention consists of the novel structure and the peculiar combinations of parts which hereinafter will be more particularly set forth and pointed out in the subjoined claims, and illustrated in the drawings hereto attached, in which:

Figure 1 is a perspective view of a section of country through which a stream flows, showing the application of the invention. Fig. 2 is a side view of the invention on a larger scale. Fig. 3 is a transverse section of the device on the line $x-x$ of Fig. 4. Fig. 4 is a view in elevation of an end portion of the device.

Corresponding and like parts are referred to in the following description and indicated in all the views of the drawings by the same reference characters.

The jetty device or bank protecting means consists of a shaft 1 which may be of any length and constructed of metal, wood or any material. One or more wings 2 are fitted to the sides of the shaft and extend lengthwise thereof in parallel relation. The wings 2 terminate a short distance from the extremities of the shaft so as to leave the end portions of the shaft projecting to form attaching points for the anchoring means. The wings 2 may be of metal or wood and secured to the shaft 1 in any substantial way. The upper outer corners of the wings are cut away to prevent engagement with the bed of the stream or river. A series of clips 3 serve to connect the wings in series and to form attaching means

between said wings and the shaft, said clips embracing the shaft and having outer ex-

tensions 4 which are riveted or otherwise secured to the wings. Each clip consists of a curved portion 5 and outwardly diverged projections 4, the curved portions 5 unitedly 60 encircling the shaft, and the outer projections 4 of the opposing ends of the adjacent clips embracing opposite sides of a wing secured together and to said wing by the same fastening means 6.

When it is required to prevent the bank of a river or stream from washing out or to reclaim a section of land or country covered by the water of the river or stream overflowing its banks, the device is arranged at the required point so as to change the current or to produce a counter-current, the effect of which is to cause the sand, silt or other earthy matter with which the waters are laden to deposit and thereby fill in the space. 70 The device is arranged at an inclination to the current so as to divert the same and effect precipitation of the sand and earthy matter carried along by the flowing water. As shown in Fig. 1, one end of the shaft is 80 anchored in the bank and the opposite end projects out into a stream and is connected by means of a cord or rope 7 with a pole or stake 8 placed upon the bank a short distance from the stream and held in position by means of stays 9 which are pinned to the earth. In the construction shown in Fig. 2, the device is inclined and both projecting ends of the shaft 1 have cords or cables 10 fitted thereto, the same adapted to anchor in 90 any manner.

When the device is placed in position, it retards, in a measure, the flow of the water or changes the current, with the result that the solid matter contained in the water is deposited and thereby fills in the land or up-builds the bank, thereby preventing further encroachment or washing out of the same. The device, after performing the desired result in one location, may be removed to another point and used repeatedly. It is to be understood that the device may be of any length and diameter and that the number of wings fitted to the shaft may be varied according to the location and the nature of the 105 stream and soil.

Having thus described the invention, what is claimed as new is:

1. Means for preventing the washing away of river banks and reclaiming land covered by the waters of a stream overflowing its banks, said means consisting of a shaft and a

wing extended lengthwise of the shaft and having positive connection therewith at intervals in its length, and said means being adapted to be placed in the stream and inclined to the current thereof to cause precipitation of solid matter with which the flowing water is laden.

2. A jetty device of the character specified, the same consisting of a shaft, and wings arranged lengthwise thereof and terminating a short distance from the extremities of the shaft to provide engaging means for the anchoring or securing device when the contrivance is in operative position.

15 3. A jetty device comprising a shaft, a series of wings grouped about the shaft, and clips for connecting the wings to one another and to the shaft, the clips comprising por-

tions adapted to encircle the shaft and other portions embracing opposite sides of the wings.

4. The herein described jetty device, consisting of a shaft, a series of wings arranged lengthwise of the shaft and grouped about the same and having their outer corners cut away, and clips, each consisting of a curved portion to embrace a part of the shaft and outer projections, the latter extending under side the wings and secured thereto.

In testimony whereof I affix my signature in presence of two witnesses:

GEORGE T. WELLS. [I. S.]

Witnesses:

DANIEL E. BOONE,
CHAS. G. YANKEY.
